UNITED STATES PATENT OFFICE.

BURQUEST MARKLE BRAE, OF BELLEVUE, PENNSYLVANIA.

SASH-LOCK.

1,088,526.

Specification of Letters Patent.

Patented Feb. 24, 1914.

Application filed June 18, 1913. Serial No. 774,347.

To all whom it may concern:

Be it known that I, BURQUEST MARKLE BRAE, a citizen of the United States of America, residing at Bellevue, in the county 5 of Allegheny and State of Pennsylvania, have invented certain new and useful Improvements in Sash-Locks, of which the following is a specification, reference being had therein to the accompanying drawing.

10. This invention relates to sash locks, and the primary object of my invention is to furnish the sash of a window with a device that can be easily and quickly swung into position to prevent the sashes of a window 15 from being opened to that extent that a person could surreptitiously enter a room or apartment.

15. A further object of this invention is to provide a simple, durable and inexpensive 20 sash lock that can be easily and quickly installed, the location of the lock being such that it cannot be tampered with by a burglar or other person.

25. With the above and other objects in view the invention resides in the novel construction, combination and arrangement of parts to be hereinafter specifically described and then claimed.

30. Reference will now be had to the drawing, wherein:—

Figure 1 is a perspective view of the sash lock, Fig. 2 is a side elevation of the same, and Fig. 3 is a front elevation of the lock.

35. A lock in accordance with this invention comprises an oblong plate 1 provided with openings 2 for screws 3, whereby said plate can be secured to the side rail 4 of an upper sash, adjacent to the meeting rail 5 of said sash. The upper end of the plate is bent 40 to form a yoke 6, and extending through said yoke is a screw 7 that cooperates with the screws 3 in retaining the plate 1 in engagement with the rail 4. Pivottally mounted upon the screw 7, within the yoke 6 is a 45 latch 8 having a finger piece 9. The upward movement of the latch 8 is limited by the top of the yoke 6 and to hold said latch at right angles to said plate, the plate 1 is

slotted, as at 10 and the slotted material bent to form a resilient detent 11. The detent 50 11 is of such length as to engage under the latch 8 and to hold the same in a horizontal position in the path of the lower sash 12 of the window. It is therefore apparent that the lower sash 12 when raised will impinge the latch 8 and further upward movement of the lower sash is prevented. Of course the upper sash cannot be lowered on account of the latch striking the meeting rail of the lower sash. When it is desired 60 to raise the lower sash or lower the upper sash the resilient detent 11 is pressed in the plane of the plate 1 and then the latch 8 can be swung downwardly into parallelism with said plate. 65

One embodiment of the invention has been illustrated, but it is to be understood that the structural elements are susceptible to such variations and modifications as fall within the scope of the appended claims. 70

What I claim is:—

1. A sash lock comprising a plate, a yoke carried by the upper end of said plate, a latch having one end pivotally mounted in said yoke and adapted to be swung upwardly at right angles to said plate, and a resilient detent forming part of said plate and adapted to extend under the lower edge of said latch. 75

2. In a sash lock, the combination with 80 the rail of an upper sash, of a plate secured thereto, a yoke carried by the upper end of said plate, a latch pivotally mounted in said yoke and limited in its upward movement by said yoke, a finger piece carried by said 85 latch, and a resilient detent formed by slitting said plate, said detent normally engaging under the lower edge of said latch for maintaining said latch at right angles to said plate. 90

In testimony whereof I affix my signature in the presence of two witnesses.

BURQUEST MARKLE BRAE.
